UNITED STATES PATENT OFFICE.

JAMES A. HOGSTEN AND WILEY A. KILGORE, OF BANKHEAD, ALABAMA; SAID HOGSTEN ASSIGNOR TO JAMES R. USREY, OF BANKHEAD, ALABAMA.

MAGNETIC CALCULATOR AND INDICATOR.

Application filed January 8, 1925. Serial No. 1,275.

To all whom it may concern:

Be it known that we, JAMES A. HOGSTEN and WILEY A. KILGORE, citizens of the United States, residing at Bankhead, in the 5 county of Walker and State of Alabama, have invented certain new and useful Improvements in Magnetic Calculators and Indicators; and we do hereby declare the following to be a full, clear, and exact description 10 of the invention, such as will enable others skilled in the art to which it appertains to make and use the same.

The primary object of this invention is the provision of an attachment to be applied to or form the back of a tablet, said attachment including a calculator and indicator for designating the product of a multiplicand and multiplier, said attachment comprising a rotatable disk provided 20 with numbers in sets, each set including a multiplicand and multiplier, and said disk being provided with an attractor such as steel or iron to draw a magnetic needle which is movable over a dial containing 25 numbers which represent the products of the several sets of numbers provided on the said rotatable disk, the magnetic needle indicating the product of the set of numbers exposed to view through an observation 30 opening of the dial.

Other objects and advantages will be apparent and suggest themselves as the nature of the invention is understood.

While the drawings illustrate an embodiment 35 of the invention it is to be understood that in adapting the same to meet different conditions and requirements, various changes in the form, proportion and minor details of construction may be resorted to 40 without departing from the nature of the invention.

Referring to the accompanying drawings forming a part of the specification,

Figure 1 is a plan view of an article of 45 the nature aforesaid embodying the invention.

Figure 2 is a sectional view on the line 2-2 of Figure 1.

Figure 3 is an enlarged sectional view of 50 the central portion of the article.

Figure 4 is a front view of the rotatable disk provided with the attractor and the set of numbers such as the multiplicand and multiplier, and

55 Figure 5 is a detail view of the attractor.

Corresponding and like parts are referred to in the following description and designated in the several views of the drawings by like reference characters.

The numeral 1 denotes the dial which corresponds to the back of the tablet or other supporting base upon which appears numbers 2 arranged in a circle and corresponding with the products of the several sets of numbers provided upon a disk 3 located in 60 the rear of the dial 1 and pivoted thereto, an edge portion of the dial 1 being cut away as indicated at 4 to expose an edge portion of the disk 3 whereby the latter may be rotated by engagement of a digit 65 of the hand therewith. The numeral 5 designates the set of numbers such as the multiplicand and multiplier provided upon the disk 3 and arranged in a circle so as to be exposed through an observation opening 70 75 formed in the dial or base 1.

Referring to Figure 1 the disk 3 is adjusted so as to bring a set of numbers, 9 multiplied by 7 opposite the observation opening 6 and the product of such numbers 80 is designated by a hand or magnetic needle 7 which points to the number 63.

An attractor 8 is mounted upon the disk 3 and preferably consists of iron or steel which is susceptible of being magnetized or 85 to attract a magnet such as the needle 7 which is mounted to turn freely. The attractor 8 is fast to the disk 3 and its ends 9 are thickened so as to extend through 90 openings formed in the disk 3 and come about flush with the face thereof bearing the sets of numbers 5 and as the disk 3 is rotated the attractor 8 moving therewith attracts the hand or magnetic needle 7 so as to properly position the same on the dial 95 1 to indicate the products of the numbers appearing opposite the observation opening 6.

The base 1 is relatively thick and the hand or magnetic needle 7 is mounted and 100 is free to turn to follow the movements of the attractor 8 and the disk 3 is mounted so as to be turned to bring any required set of numbers to be multiplied opposite the opening 6 when the product will be indicated on the dial by the hand 7 as shown most clearly in Figure 1. The several parts are concentrically mounted, the pivot connection 10 being of any preferred construction best adapted for the purpose. A back- 110

ing 11 such as a piece of paper or other sheet material covers the rear side of the disk 3 and the attractor 8 applied thereto.

What is claimed is:—

- 5 1. A calculator and indicator comprising a dial provided with a series of product numbers, a magnetic hand adapted to move over the dial, a disk provided with sets of numbers, each set of numbers including a
- 10 multiplicand and a multiplier, said disk being movable to bring a set of numbers opposite an observation opening formed in the dial, and a magnetic attractor carried by the disk to cause the magnetic hand to
- 15 follow the movements of the disk and designate the product of the numbers appearing opposite the said observation opening.
2. A magnetic calculator and indicator comprising a dial having an observation

opening and provided with a plurality of 20 product numbers arranged in a circle, a magnetic hand movable over the dial, a disk disposed in the rear of the dial and provided with sets of numbers arranged in a circle, each set of numbers including a 25 multiplicand and a multiplier, and a magnetic attractor carried by the disk and located in the rear thereof and having its ends extended into openings formed in the disk, said attractor causing the magnetic 30 hand to follow the movements of the disk to indicate the product of the set of numbers appearing opposite the said observation opening.

In testimony whereof we affix our signatures.

JAMES A. HOGSTEN.
WILEY A. KILGORE.
